TABLE CONSTRUCTION

Arthur J. Kizaur, Cicero, Ill., assignor to General
Electric X-Ray Corporation, Chicago, Ill., a cor-
poration of New York

Application July 19, 1946, Serial No. 684,650

13 Claims. (Cl. 250—57)

1

The present invention relates in general to tables, and has more particular reference to a tilting structure particularly well adapted for use in supporting human bodies, selectively in vertical and horizontal positions for examination, the table structure of the present invention being especially adapted for use in connection with X-ray fluoroscopic examination and for radiographic purposes.

An important object of the present invention is to provide an improved, light weight, yet rigid table structure, including tilting support means for carrying the table in, and shifting the same between, vertical and horizontal positions; a further object being to provide improved tilting support means operatively connected with the table along one side thereof, thereby leaving the other side free and unobstructed.

Another important object is to provide a tilting table supported on one side only, whereby carrying means for radiographic, or other equipment may be mounted on the table for unhampered adjustment along the unsupported side of the table.

Another important object is to provide a table structure of the character mentioned, and comprising a framework of hollow tubular members interconnected to form a rigid, light weight table structure; a further object being to form the table as a frame, including tubular side members extending longitudinally on each side of the table in position to carry a table top panel and in position extending between the longitudinal side members; a still further important object being to utilize the tubular table frame members to house actuating mechanism therein.

Another important object is to provide novel table tilting means, comprising relatively crossed members tiltingly interconnected between the table structure and a supporting base, in conjunction with thrust mechanism for supporting the crossed members in adjusted, relatively crossed position, and, hence, to support the table mounted thereon at a desired adjusted inclination; a further object being to form at least one of said crossed members as a tube, such tube being inexpensive, yet affording appreciable rigidity.

Another important object resides in utilizing tubular members suitably fastened together, as by welding or otherwise, to provide a rigid table supporting base.

Another important object resides in utilizing hydraulic means for actuating the table tilting mechanism; a further object being to incorporate the hydraulic means compactly in the sup-

2

porting base of the table and in the table structure.

Another important object resides in providing hydraulic control means in a table for X-ray fluoroscopy and roentgenological purposes.

Another important object resides in providing a table and associated support means for mounting X-ray apparatus for adjustable movement longitudinally of the table, including hydraulically actuated and controlled means for so moving the associated X-ray equipment; a further object being to provide for such control in a tilting table, wherein the table itself is operatively connected with the hydraulic actuating system, to the end that the tilted adjustment of the table, as well as the longitudinal adjustment of the associated X-ray apparatus, may be accomplished by hydraulic control valves, all conveniently located at a control station on one side of the table.

Another important object resides in providing improved hydraulic means for the control of a tiltable table of the character mentioned, and for the control of adjustable apparatus mounted on the table.

Another important object is to provide an improved tilting table construction that is unusually light in weight, the structure having, at the same time, extraordinary rigidity.

The foregoing and numerous other important objects, advantages, and inherent functions of the invention will become apparent as the same is more fully understood from the following description, which, taken in connection with the accompanying drawings, discloses a preferred embodiment of the invention.

Referring to the drawings:

Fig. 1 is a perspective view illustrating a table structure embodying the present invention, the view showing longitudinally adjustable carriage means for supporting auxiliary equipment;

Fig. 2 is a sectional view along the line 2—2 in Fig. 1;

Figs. 3 and 4 are enlarged views of portions of Fig. 2;

Fig. 5 is a top plan view of the table shown in Fig. 1;

Figs. 6, 7, and 8 are sectional views, respectively taken substantially along the lines 6—6, 7—7, and 8—8 in Figs. 1, 5, 6, and 7;

Fig. 9 is a diagrammatic view showing an hydraulic system that may be incorporated in the structure shown in Fig. 1; and

Fig. 10 is a perspective view of a table embodying the present invention and applied for

use with separately mounted and longitudinally adjustable auxiliary equipment.

To illustrate the invention, the drawings show an adjustable table structure 11 particularly well suited for supporting bodies for examination, the structure being especially adapted for X-ray examination and therapy purposes, in that it is tiltably supported for movement between horizontal and vertical positions, and may be secured at any desired inclination between its horizontal and vertical positions in order to support a body thereon at any desired inclination. The table structure, further, is well adapted for the adjustable mounting thereon of auxiliary apparatus, such as an X-ray light source, screens, diaphragms, and holders of X-ray sensitive film material, which may be mounted on the table for longitudinal and lateral adjustment, substantially in the manner taught in United States Letters Patent No. 2,315,786, issued April 6, 1943, on the invention of Julius J. Grobe.

The table structure 11 comprises a frame 12 and adjustable support means 13 carrying the frame; and the present invention includes not only the novel features of the light weight, hollow frame structure, but, also, the features of the rigid table support structure 13, as well as hydraulic operating means 14 for actuating the adjustable support means 13, the hydraulic means serving, also, to actuate adjusting means 15 housed, preferably and conveniently, within the hollow members comprising the frame 12, for the purpose of adjusting holder frames 16 and 17 longitudinally on the frame 12, and, if desired, to adjust a frame 18 on the frame 17 transversely with respect to the frame 12, the frame 18 serving to support auxiliary equipment, such as a source of X-rays 19, and a fluoroscopic screen 19', adjustably above the table.

The frame 16 may comprise a mounting for a film holder and a bucky diaphragm, the same being provided with bearing wheels 20 on opposite sides thereof, in position to ride upon suitable track means 21 on the frame 12, so that the mounting frame 16 may be moved longitudinally along the table 12. The frame 17, also, may be provided with wheeled means 22 mounted on the table frame for movement longitudinally thereof, in tracks 22' on the frame 12, said frame 17, in turn, supporting the frame 18, which preferably includes transversely extending members 23 supported by suitable rollers 24 on the frame 17 for movement of the frame 18 transversely with respect to the table frame 12. The frame 18 may include an upstanding portion 25 supported outwardly of the frame 12, at one side thereof, said upwardly extending portion serving as a mounting for suitable support means, which may be adjustable vertically on the said upstanding portion for the purpose of carrying a source of X-rays and, also, fluoroscopic screen means in vertically spaced relationship with respect to the table, the screen means and source of X-rays being independently adjustable on the upstanding frame portion 25, as, for example, in the manner taught in said aforesaid United States Letters Patent No. 2,315,786. The frames 16, 17, and 18 may be formed in any suitable, convenient or preferred fashion, the aforesaid United States Letters Patent No. 2,315,786 showing suitable, relatively movable frame means of the sort that may be employed, and the manner of mounting the same for movement upon the table frame. Suitable table top means 26, also, may be applied on the frame 12 in position overlying the frames 16 and 17, in

the manner taught in said aforesaid United States Letters Patent No. 2,315,786, for the purpose of supporting a body on the table.

The present invention contemplates the fabrication of the frame 12 of hollow, sheet metal members, including a pair of spaced apart, longitudinally extending, hollow, sheet metal frame members 27 and 28 of preferably rectangular sectional configuration. The opposite ends of the longitudinal members 27 and 28 are rigidly interconnected in spaced relationship by transverse bracing and spacing members 29 and 30. The members 29 and 30, also, preferably comprise tubular members of metal, having preferably rectangular sectional configuration, although it will be apparent that the present invention is not necessarily limited to the rectangular sectional shape of the frame members. The frame members forming the frame 12 may be secured together in any suitable or convenient fashion, the same being preferably interconnected, as by welding, the members preferably comprising steel parts that are particularly well suited for inexpensive, yet rigid interconnection in the manner mentioned. The frame 12 may, thus, comprise a rectangular structure made of tubular frame members rigidly interconnected together, the preferred box-like character of the frame members affording a structure of unusual rigidity.

30 The frame member 28, on one side of the frame, is preferably substantially deeper than the member 27, on the other side of the frame. The frame member 28 is made deeper more especially to allow the frame 17 to be rollingly mounted on tracks supported at the inner face of the member 28, and to allow the transverse members 23 of the frame 18 to project outwardly of the frame 12 beneath the member 27. The additional depth of the frame member 28, also, increases its rigidity

35 to an extent allowing the frame to be mounted on the support means 13 only at the side thereof comprising the member 28, the other side of the frame being unsupported and entirely free of obstruction, so that the frame 18 may traverse the frame 12 longitudinally throughout the entire length of the frame 12.

40 The hollow members comprising the frame 12 may be utilized, to advantage, to entirely enclose the actuating means 15. Said actuating means 50 may comprise a spindle mounted pulley 31 disposed within the member 28, the pulley 31 preferably having four cable grooves in its periphery. The spindle, which carries the pulley 31, may be supported on a bracket 32 which, in turn, 55 may be connected to a plunger or piston 33, operating in an hydraulic cylinder 34 and comprising means for adjusting the position of the pulley 31 longitudinally within the frame member 28. While any suitable mechanism may be 60 employed for so adjusting the pulley, hydraulic means, comprising the piston and cylinder 33 and 34, affords a compact mechanism housable within the member 28 for accomplishing the adjusting movement of the pulley 31. The bracket 65 32, as shown more particularly in Figs. 7 and 8 of the drawings, may be provided with roller wheels 35 adapted to bear on the inner walls of the member 28, in order to support the pulley 31 for longitudinal movement within the member 70 28. The hydraulic cylinder 34, also, may be mounted within the member 28, as by means of mounting brackets 34' at its opposite ends. A pair of flexible driving members 36, having ends anchored upon a suitable mounting 37 formed on 75 and within the member 28, preferably at one end

thereof, extend from the mounting 37 around the pulley wheel 31 and thence on guide means 38, preferably comprising a pulley, disposed within the transverse bracing member 30, at the end thereof which is connected with the member 28. The pulley 38 is preferably formed with two grooves, and one of the cords 36 extends around the guide pulley 38 through an opening in the inner wall of the member 30, and is connected on the frame 17. The other cord 36 extends around the guide pulley 38 and thence through the frame member 30, and around a guide pulley 39 disposed in the member 30, at the end thereof which is connected with the member 27, the cord extending from the guide pulley 39 through an opening in the inner wall of the member 30, and being connected to the frame 17.

A second pair of flexible driving members 40, having ends anchored within the member 28, as on the mountings 41 on one of the brackets 34', extend thence around the pulley 31 and through the member 28, to the end thereof that is connected with the transverse frame member 29, the driving members 40 passing over guide means 42, similar to the guide means 38 and located in the end of the transverse member 29 adjacent the frame member 28. One of the cords 40 passes around the guide means 42, through an opening in the inner face of the member 29, and is connected to the frame 17. The other driving member 40 passes around the guide means 42, and thence through the transverse member 29 to a guide 43, corresponding with the member 39 and located in the end of the transverse member 29 that is connected with the frame member 27, said driving member passing around the guide 43, thence through an opening in the inner face of the member 29, and being connected with the frame member 17. The driving members 36 and 40 are, thus, connected to the opposite ends of the frame 17. Hence, by moving the pulley 31 longitudinally within the frame member 28, the frame 17 may be drawn longitudinally in either direction on the frame 12.

The support means 13 is adapted to tilt the frame 12 from the horizontal position, shown in Fig. 1, to a vertical position by lowering the right hand end of the frame, viewing Fig. 1, while raising the left hand end thereof. When so tilted, it will be obvious that the frame 17, under the influence of gravity, will tend to move toward the lowered or right hand end of the frame. The tendency of the frame 17 thus to move in one direction on the frame 12, when the same is tilted, will tend to move the pulley 31 in the opposite direction within the frame member 28. The cylinder 34 and piston 33, however, are preferably mounted in the frame so that such tendency to move is counterbalanced by the pressure of operating fluid in the cylinder. Additional counterbalancing means, such as weights or springs, also may be connected to the pulley bracket 32, if desired.

The piston 33 is adapted to be moved outwardly of the cylinder 34 in response to liquid delivered in the cylinder. To retract the piston when liquid is released from the cylinder, retracting means, preferably comprising tension springs 44, may be applied within the member 28 and connected, as on suitable anchors 45, on the frame 12, as at one end of the member 28, said springs preferably extending in guide tubes 46, and being connected on anchoring lugs 47 formed on the bracket 32.

Means for shifting and counterbalancing the 75 as at 67, on the frame means 62. The other end

carriage 16 may, also, be provided, such means being conveniently disposed within the hollow frame member 27. Such actuating and counterbalancing means for the carriage 16, as shown more particularly in Figs. 5 and 6 of the drawings, may comprise an hydraulic piston and cylinder 48 and 49, similar to the piston and cylinder 33 and 34, and mounted within the member 27, as by means of brackets 49' at the opposite ends of the cylinder 49, for securing and supporting the same within the member 27. The piston carries a bracket 50, in which may be turnably mounted a pulley 51 having four grooves. A pair of preferably flexible driving members 52 ride in two of the pulley grooves, said members 52 having ends anchored, as at 53, at one end of the member 27, the driving members 52 extending thence around the pulley 51 and around guide pulleys 54 at one end of the member 27, and thence through an opening in the upper face of the member 27 to a guide pulley 55 supported above the upper face of the member 30, at the end thereof which is connected with the member 27. From the guide pulley 55 one of the members 52 extends to, and is anchored on, the carriage 16, while the other member 52 extends to the end of the member 30, which is connected with the member 28, and extends thence around a guide pulley 56 to the frame 16 on which it is fastened.

The pulley 51 also carries a second pair of flexible tension members 57, which have ends anchored, as at 58, within the member 27, as on one of the brackets 49', the members 57 extending thence around the pulley 51 and around guide pulleys 59, 60, and 61, corresponding with the guide pulleys 54, 55, and 56, the members 57 being connected with the carriage 16. It will be seen that the members 52 and 57 are, thus, attached at opposite ends of the carriage 16, so that by moving the pulley 51 longitudinally within the member 27 by actuating driving means 48 and 49, the carriage 16 may be adjusted longitudinally of the frame 12.

The weight of the carriage, of course, may be appreciably less than the weight of the frames 17 and 18, and, consequently, does not require counterbalancing, where the actuating means 49 comprises an hydraulic piston and cylinder. If desired, however, counterbalancing means, such as weights or springs, may be applied within the member 27 and operatively connected with the pulley carrying bracket 50.

The foregoing table frame construction affords relatively light weight, yet extremely rigid table means which may be supported in any preferred fashion. Because of its unusual inherent rigidity, however, the table construction is particularly well adapted for support along one side only, the other side being entirely free and unobstructed; and the present invention contemplates the provision of novel, and relatively inexpensive, tilting support means 13 for carrying the table. As shown, the support means 13 comprises a base 62 of any suitable construction, the base preferably comprising a rectangular frame of preferably welded interconnecting tubular members, including side members 63 and end members 64, said members preferably comprising cylindrical tubes or pipes of metal, such as steel.

The adjustable table supporting means 13 may be of any suitable construction, and preferably comprises a pair of relatively crossed members 65 and 66; the member 65 having an end pivoted,

of the member 65 may be pivoted, as at 68, on suitable bracket means medially of the ends of the frame member 28. As shown, the member 65 preferably comprises a hollow tubular pipe affording strength and rigidity at low cost.

The member 66 preferably comprises a pair of sheet metal plates 69, having ends pivoted, as at 70, on the base 62 vertically beneath the pivoted connection of the member 65 on the frame member 28. The members 69 extend on opposite sides of the member 65, crossing the same, and have remote ends pivotally connected, as at 71, on suitable bracket means on the frame 12, at an end of the member 28.

By turning the member 65 on the frame 62 about the pivot 67, it may be moved between the members 69 in a direction toward and away from the ends of the members 69 that are pivoted on the frame 12. As a result of such pivoting movement of the member 65, the supported table frame 12 may be tilted in the manner heretofore described, between the horizontal position, shown in Fig. 1, and a vertical position in which the right hand end of the frame 12, viewing Fig. 1, is disposed immediately above the pivot 67, with the left hand end of the frame 12 vertically above its right hand end.

Any suitable operating mechanism, of course, may be utilized for turning the member 65 with respect to the base 62. To this end, extensible screw means may be applied between the pivots 68 and 70. As shown in the drawings, however, means, comprising an hydraulic cylinder 72 and a cooperating piston 73, is mounted within, and as a part of, the member 66, the cylinder 72 being secured on and between the members 69, so that the cylinder is rigidly connected with said members and, hence, movable therewith on the pivot 70. The piston member 73 projects toward the member 65 and carries a bracket 74, in which is mounted a driving roller 75 in position to engage and ride upon the surfaces of the member 65, which may, if desired, be provided with a plate 76 forming a bearing track for the roller. By operating the hydraulic means 72 to project the piston 73, the member 65 may be moved in a direction toward the pivot 71 in order to tilt the supported table 12 toward vertical position. By retracting the piston, the table may be returned to the horizontal position shown in Fig. 1; and by regulating the operating means 72, the table may be supported in vertical, or horizontal, or at any intermediate inclination. It is desirable, also, to provide means normally biasing the table toward horizontal position. To this end, a flexible traction member 77 may be provided, having an end anchored on the frame member 28, as at a suitable point between the trunnions 68 and 71, and spaced from the latter a sufficient distance to apply an appreciable turning movement on the frame about the axis of said trunnion 71. The tension member 77 may extend around a guide roller or pulley 78 on the base 62, and may be connected on one end of a resilient tension spring 79, the other end of which is secured, as on a suitable anchor 80, on the base 62. Tension thus applied to the frame, when in vertical position, by the member 77, will yieldingly urge the frame toward horizontal position, and will urge the member 65 against the roller 75 and cause said member to follow the roller as and when the plunger 73 is retracted.

It will be obvious, however, that the invention is not necessarily limited to hydraulic operating means, either for actuating the tilting mech-

anism 13, or for actuating the frame adjusting pulleys 31 and 51. The apparatus of the present invention, however, is particularly well suited for embodying hydraulic actuating means for adjusting the tilting table, and for the adjustment of the movable frames 16, 17, and 18. To this end, the adjusting means 34, 49, and 72 preferably comprise hydraulic cylinders, to which a fluid operating medium may be selectively delivered, as by the hydraulic system illustrated more particularly in Fig. 9 of the drawings. As shown, the hydraulic system includes a fluid reservoir 81, which may conveniently comprise a tank mounted in the base 62, as between the members 63, preferably at one end of the base. The hydraulic system may include a pump 82 driven by motive means, such as an electric motor 83, the pump having an inlet pipe 84 from the reservoir, the pipe preferably being fitted with filtering means 85, as at its reservoir connected end. The discharge side of the pump 82 may be connected with a delivery conduit system 86, including branch conduits 87 and 88 connected, respectively, through adjustable valves 89 and 90, for selectively controlling the flow of hydraulic fluid through the pipes 87 and 88 to the operating cylinders of the frame shifting devices 34 and 49. Another branch pipe 91 connects the delivery conduit system through a valve 92 with the table tilting device 72, while additional conduit means 93 may be provided for connecting the delivery system through valves 94 to operating devices 95, for the actuation of other operable devices on, or associated with, the table structure, as, for example, for adjusting the frame 18 laterally of the table on the frame 17, for adjusting a support frame vertically on the frame portion 25, for operating latch mechanism to secure the frames 16, 17 and 18 in adjusted position, or for operating other auxiliary equipment.

The pump 82 is preferably driven continuously by the motor 83 to maintain a supply of the hydraulic medium in the conduit system 86, at a selected operating pressure determined by check valve means 96 disposed in a conduit 97, connected between the conduit system 86 and the reservoir. When fluid pressure in the system 86 exceeds a preselected value, determined by the adjustment of the check valve 96, fluid may circulate directly from the system 86 to the reservoir for recirculation through the pump. The valves 89, 90, 92, and 94 are, also, preferably connected with conduit means 98 forming a return flow system to the reservoir 81.

The valve means 89, 90, 92, and 94 comprise manually operable valves for connecting the devices 34, 49, 72, and 95, either with the supply system 86, or with the return flow system 98, and, also, provide for blocking connection of said devices 34, 49, 72, and 95 with either of said systems, whereby the devices may be actuated in one direction or the other, or locked in adjusted position.

The devices 34, 49, 72, and 95 may be of any suitable, preferred or convenient construction, and the operating valves 89, 90, 92, and 94, likewise, may have any suitable or preferred form. As shown, the device 49 comprises a cylinder, and its cooperating thrust member 48 comprises a piston rod having a piston head 99 within the cylinder. The opposite ends of the cylinder 49 are connected by means of the conduits 100 with the valve 90. The valve 90 comprises a valve member 101, which may be arranged selectively in any one

of three positions, to connect either end of the cylinder 49 with the fluid supply system 86, while connecting the other end of the cylinder with the return system 98; or the member 101 may be positioned to block connection of both pipes 100. The member 48 may, thus, be projected or retracted through a displacement equal to the displacement of the piston head 99 within the length of the cylinder, and the member 49 may be locked in place with the piston head 99 in any intermediate position between the opposite ends of the cylinder 49. As a consequence, the carriage 16 may be moved to, and locked in, any adjusted position at or between the opposite ends of the frame 12.

As shown, the device 34 comprises a cylinder in which the cooperating piston rod 33 fits snugly, one end of the cylinder 34 only being connected, as by means of a pipe 102, with the valve 89, the piston 33 being normally urged, as by means of the springs 44, toward said end of the cylinder. The valve 89 comprises a valve member 103, positionable to connect the conduit 102 with the supply system 86, whereby to deliver fluid under pressure into the cylinder 34 for the projection of the piston 33 in one direction outwardly of the cylinder, against the influence of the springs 44. The valve member 103 is, also, positionable to connect the conduit 102 with the return system 98, whereby the piston 33 may be retracted into the cylinder 34, under the influence of the springs 44. The valve member 103 may, also, be positioned to block connection of the conduit 102 from either system, in order to lock the piston 33 in any relatively extended position with respect to the cylinder 34. As a consequence, the carriage 16 may be adjusted and locked in any adjusted position at and between the opposite ends of the table frame 12.

The table tilting device 72 preferably comprises a cylinder, from one end of which the extensible piston member 73 projects, the opposite end of the cylinder being connected, as by means of a conduit 104, with the valve 92. The valve 92 comprises a movable member 105, which may be positioned to connect the conduit 104 with the fluid supply system 86, in order to project the piston member 73 outwardly of the cylinder, against the weight of the table applied to the piston through the member 65 and the bearing roller 75. The valve member 105 may, also, be positioned to connect the conduit 104 with the return system 98, to allow retraction of the piston 73 within the cylinder, under the influence of the weight of the table. The member 105, also, may be positioned to block connection of the pipe 104 from the supply and return systems, in order to lock the piston member 73 in any adjusted position within the cylinder 72. If desired, an extension sleeve 106 may be applied telescopically around the piston member 73 within the cylinder 72.

The valve members 94 likewise provide for the selective connection of the devices 95 with the systems 86 and 98 for the operation of said devices.

The table, shown in Fig. 1 of the drawings, carries the frames 17 and 18, which are adapted to support an X-ray tube and, if desired, a fluoroscopic screen, adjustably in position above or below the table. The X-ray light source and screen, thus, may be supported directly on the table frame. For some purposes, however, it may be desirable to dispense with the frames 17 and 18, and to mount the X-ray source and the

fluoroscopic screen, if used, on a separate support structure, as shown in Fig. 10. To this end, a support standard, comprising an upright post 107, may be provided and mounted, as on suitable trackways 108 and 109, for movement longitudinally of the table frame 12, along one side thereof. To this end, the trackways 108 and 109 may comprise channel members adapted to receive mounting rollers at the upper and lower ends of the post 107. The lower end of the post is preferably formed with a base 110, in which track engaging rollers 111 are mounted to rollingly support the upright 107 for movement along the trackway 109. A manually operable track engaging latch 112 may also be provided on the base 110 for locking the member 107 and its carriage 110 in adjusted position on the track.

The upper end of the post 107, also, may be provided with a guide roller adapted to travel within the track member 108 to support the post in upright position on the track 109.

The post 107 may be provided with suitable mounting frames, preferably adjustable vertically thereon, for carrying an X-ray generator or light source in vertically adjustable position with respect to the table frame 12, such supporting means, also, preferably providing for the adjustment of the light source transversely with respect to the table frame. It is also desirable to provide for the tilting movement of the light source on the support 107, as the post 107 is moved longitudinally of the table, it being desirable, in some instances, in making radiographic pictures, to move the light source in one direction, above an object being pictured, while moving the sensitive photographic material in the carriage 16 in an opposite direction beneath the object being pictured. Such procedure results in the production of an accurate, sharp picture of an internal portion of the object being radiographed, while blurring, and thus obliterating, surrounding portions of the object. To provide for making radiographs of the character mentioned, the support post 107 may be provided with a frame 113, tiltably mounted on the post, and vertically adjustable thereon, as by means of a suitable bracket 114. The frame 113, as shown, comprises a pair of spaced bars 115, preferably extending transversely with respect to the table frame, and on which bars a source of light may be mounted for adjustment transversely of the table frame. The frame 113 may be provided with a downwardly extending actuating rod 116 pivotally connected, as at 117, on bracket means 118 adapted to be clamped upon the table frame 12, as on the member 27 thereof, in any adjusted position longitudinally of the member 27. When so clamped, it will be seen that movement of the support 107 along its track 109 will result in a corresponding tilting movement of the frame 113, and any light source mounted thereon, about the pivotal mounting axis of the frame 113 in the bracket 114. While such pivoting movement is accomplished, a corresponding movement of the carriage 16 may also be accomplished in the opposite direction by suitably controlling the valve 90. In order to control the movement of the member 107 on its track 109 accurately, whereby to determine the corresponding movement of the frame 113, the member 107 may be provided with driving means, comprising a wheel 119 having any preferred driving engagement with the track 109, said wheel, as shown in Fig. 10 of the drawings, comprising a sprocket or pulley drivingly connected with a loop formed in a flexible driv-

ing member 120. The member 120 extends within the channeled track member 109 and is anchored therein at its opposite ends. The member 120 has a medial loop forming portion drivingly connected with the wheel member 119, the member 120 extending from the track to the wheel around suitable guides 121 mounted on the base 110. By turning the member 119, the support 107 may be drawn in one direction or the other along the track 109 through a displacement determined by the movement of the wheel 119. Any suitable means, of course, may be provided for turning the wheel 119 in order to accomplish movement of the support 107 on the track. As shown, however, the wheel 119 is drivingly connected through gear means 122 with a rack formed on the projecting end of the piston of an hydraulic cylinder 95', which may comprise one of the operating devices 95 heretofore described. The rack is normally urged in one direction inwardly of its cooperating cylinder, as by means of a spring 123, so that by selectively actuating a valve 94', which is operatively associated with the device 95' and the hydraulic system 14, the wheel 119 may be turned in either direction to accomplish a corresponding traveling movement of the support 107 on the track 109 and longitudinally of the table frame 12. By correlating the movement of the valve 94' with the movement of the valve 90, the movement of a light source on the frame 113 may be accurately correlated with the movement of X-ray sensitive material in the carriage 16, whereby a radiograph of the sort heretofore described may be made.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. A table for X-ray examination comprising hollow sheet metal members of rectangular sectional configuration rigidly interconnected to form a table frame having spaced apart, longitudinal side members, carriage means adjustably shiftable longitudinally of said frame, a support structure pivotally connected with said frame solely on one side thereof, on one of said longitudinal side members, for mounting the frame, in cantilever fashion, as a tilting table, actuating means mounted within and enclosed by one of said longitudinally extending table frame members for shifting said carriage on the frame, and hydraulically actuated means for tiltingly adjusting said table frame with respect to said base.

2. A table for X-ray examination comprising hollow sheet metal members of rectangular sectional configuration rigidly interconnected to form a table frame having spaced apart, longitudinal side members, carriage means adjustably shiftable longitudinally of said frame, a support structure pivotally connected with said frame solely on one side thereof, on one of said longitudinal side members, for mounting the frame, in cantilever fashion, as a tilting table, actuating means mounted within and enclosed by one of said longitudinally extending table frame members for shifting said carriage on the frame, and hydraulically actuated means for tiltingly ad-

justing said table frame with respect to said base, and means providing a common source of fluid pressure for operating said hydraulic actuating and hydraulically actuated means.

3. A table for X-ray examination comprising hollow metal members rigidly interconnected to form a table frame, and a support structure for said frame including a base having spaced supports, a pair of supporting and tilting members each having a portion pivotally secured respectively each on a corresponding one of said supports on said base, said members being relatively crossed and having remote portions pivotally secured in spaced relation on said frame, and carriage means supported on and adjustably shiftable longitudinally of said frame.

4. A table for X-ray examination comprising hollow metal members rigidly interconnected to form a table frame, and a support structure for said frame including a base having spaced supports, a pair of supporting and tilting members each having a portion pivotally secured respectively each on a corresponding one of said supports on said base, said members being relatively crossed and having remote portions pivotally secured in spaced relation on said frame, and means to relatively shift said crossed members on said base to alter the supported inclination of the frame with respect to the base.

5. A table for X-ray examination comprising a base, a table frame, carriage means supported on and adjustably shiftable longitudinally of said frame, and table tilting and supporting means carrying said table on said base and comprising a tilting member and a tie link rockingly connected on spaced rocking pivots on said base, said tilting member and tie link being pivotally connected at spaced apart pivot stations on said table frame, and being relatively crossed one with respect to the other, and means to rotate said tilting member about its rocking pivot on said base.

6. A table, as set forth in claim 5, wherein said frame comprises a longitudinal member on one side thereof, said pivot stations being formed on said longitudinal member to support said frame on one side thereof.

7. A table, as set forth in claim 5, wherein the means to rotate the tilting member comprises a thrust member disposed in position to exert thrust between said tilting member and said base at thrust stations on said base and tilting member remote from the rocking pivot of said member.

8. A table, as set forth in claim 5, wherein the means to rotate the tilting member comprises a thrust member disposed in position to exert thrust between the rocking pivot of said tie link and portions of said tilting member spaced from its rocking pivot.

9. A table, as set forth in claim 5, wherein the means to rotate the tilting member comprises a thrust member disposed in position to exert thrust between said thrust member comprising a roller adapted for rolling engagement on said tilting member.

10. A table for X-ray examination comprising hollow metal members rigidly interconnected to form a table frame having spaced, parallel side members, a support base, support means pivotally connected on said base and having pivotal connection on one side only of said frame on one of said side members, whereby to support the frame in cantilever fashion, carriage means adjustably shiftable longitudinally of said frame,

actuating means disposed within said hollow metal members and drivingly connected with said carriage means for adjustably shifting same on said frame, said actuating means comprising a driving member supported within one of said hollow members and movable longitudinally thereof, and transmission means drivingly connecting said driving means with said shiftable support means.

11. A table for X-ray examination comprising hollow metal members rigidly interconnected to form a table frame having spaced, parallel side members, a support base, support means pivotally connected on said base and having pivotal connection on one side only of said frame on one of said side members, whereby to support the frame in cantilever fashion, carriage means adjustably shiftable longitudinally of said frame, and actuating means disposed within said hollow metal members and drivingly connected with said carriage means for adjustably shifting same on said frame, said driving means comprising a stem guidingly supported within one of said hollow members for actuating movement longitudinally thereof.

12. A table comprising interconnected frame members, including a hollow sheet metal member, forming an elongated frame having spaced, parallel side members, a support base, support means on said base and having pivotal connection at spaced support stations on one side only of said frame, a cassette carriage extending between and mounted upon said side members for adjustable movement longitudinally of said frame, panel means forming a table top on said frame in position extending above said cassette carriage, a support carriage mounted upon said side members for adjustable movement longitudinally of said frame below said cassette carriage, a mounting carriage on said support carriage and movable thereon laterally of said frame, said mounting carriage having a portion extending outwardly of the side of said frame remote from said support means and upwardly of said panel means, and actuating means disposed within said hollow member and drivingly connected with at least one of the same for shifting said carriage with respect to said frame.

13. A table comprising means forming a frame having spaced side members, a cassette carriage shiftable on and between and longitudinally of said side members, an adjustable support structure for mounting said frame, panel means forming a table top on said frame in position extending above said cassette carriage, a support carriage movable longitudinally of said table, and having support portions extending outwardly and upwardly of said frame in position to support X-ray apparatus above said panel means, means forming a track for said support carriage, and hydraulic actuating means for shifting said cassette carriage on the frame, for shifting said support carriage on its track, and for adjusting said support structure, said hydraulic means including a source of fluid pressure, and a separate hydraulic driving device for each of said cassette carriage, support carriage and said support structure and drivingly connected therewith, each said driving device being connected through a corresponding control valve with said source of fluid pressure.
